UNITED STATES PATENT OFFICE.

JOSEPH SHAPIRO, OF BALTIMORE, MARYLAND.

DESIGN FOR A CAKE CONE.

56,386.

Specification for Design.

Patented Oct. 5, 1920.

Application filed April 14, 1920. Serial No. 373,970. Term of patent 7 years.

To all whom it may concern:

Be it known that I, JOSEPH SHAPIRO, a citizen of the United States, residing at 2516 Keyworth avenue, Baltimore, Maryland, have invented a new, original, and ornamental Design for a Cake Cone, of which the following is a specification, reference being had to the accompanying drawing, forming part thereof.

The figure is an elevation of the cone showing my new design.

As shown in the drawing, the body portion A is in the form of a right cone and rising from the top of the body portion is an outwardly and upwardly curved marginal portion B.

I claim:

The ornamental design for a cake cone as shown and described.

JOSEPH SHAPIRO.
